UNITED STATES PATENT OFFICE.

ELOUILD DUPLESSIS, OF ST. HYACINTHE, CANADA, ASSIGNOR TO THE DUPLESSIS PEGGING AND SEWING MACHINE COMPANY, OF SAME PLACE.

PEGGING-MACHINE.

SPECIFICATION forming part of Letters Patent No. 651,415, dated June 12, 1900.

Application filed February 17, 1899. Serial No. 705,930. (No model.)

To all whom it may concern:

Be it known that I, ELOUILD DUPLESSIS, of the city of St. Hyacinthe, in the Province of Quebec, Canada, have invented certain new and useful Improvements in Pegging-Machines; and I do hereby declare that the following is a full, clear, and exact description of the same.

My invention although applicable to almost any type of pegging-machine is particularly applicable to a machine of the type set forth in Letters Patent of the United States granted under No. 594,466 on November 13, 1897, and No. 616,699 on December 27, 1898, and Letters Patent of the Dominion of Canada granted under No. 58,455 on December 20, 1897, and No. 62,443 on January 25, 1899.

The object of the present invention is to greatly simplify and consequently reduce the cost of the production of pegging-machines generally; and to these ends the invention may be said, briefly, to consist in arranging in a particular manner a stationary cutter carried upon an annular stationary part of the nose of the horn or work-support, said annular part having a centripetally-extending arm formed on the interior thereof and carrying a vertically-adjustable screw to support a plate. This cutter is preferably held in place by an annular part adapted also to serve as a work-supporting portion, while the before-mentioned plate, which is free of the cutter and located on the side thereof, serves, in conjunction with said annular retaining part, to support the work, the last-mentioned part being preferably adjustable in order that it may be kept constantly on approximately the same plane as the cutter.

In a pegging-machine comprising a stationary horn or work-support a knife of only sufficient length to diagonally intersect the line of travel of the driven pegs is necessary; but in a machine comprising a swinging horn the cutter should be curved concentrically of the arc in which the horn swings and be of sufficient length to at all times intersect the line of travel of the driven pegs. This latter embodiment of my invention is hereinafter described, and illustrated in the drawings, in

which like symbols indicate the same parts, 50 and wherein—

Figure 1 is a detail side elevation of the nose of a swinging horn constructed according to my invention; Fig. 2, a plan view thereof; Fig. 3, a similar view with retaining-cap removed; Fig. 4, a similar view with cutter removed; Fig. 5, a similar view with work-supporting portion removed; Fig. 6, a transverse vertical sectional view, taken on line 66, Fig. 2, of the nose of the horn with all 60 the parts assembled; and Fig. 7, a similar view taken on line 77, Fig. 2.

The nose of the horn 10 is circular in plan view and has an externally-screw-threaded annular vertical projection 12 formed integrally therewith, while the interior opening of said annular projection extends downwardly completely through the nose of the horn, as at 13. A centrolineally-projecting arm 14 is formed on the interior of the rear 70 portion of said annular projection 12 and with its inner free end located concentrically thereof and provided with a vertical screw-threaded boring 15, adapted to receive a screw 16, having its upper end flattened, to 75 be presently further alluded to. The cutter is in the form of a ring 17, having its inner edge sharpened to a knife-edge, as at 18, and this cutter is held in place by a short sleeve 20, having its upper end of reduced interior 80 diameter, as at 21, and the interior of its main body portion screw-threaded to take into the screw-threads upon the exterior of the annular projection 12. A work-supporting plate 30 is supported upon the arm 14 85 through the screw 16 and is held in place by a retaining-screw 31, taking through the plate into said arm 14. This work-supporting plate has its inner end curved concentrically of the cutter and its outer end made to conform to 90 the contour of the interior of the annular projection 12, while the space intermediate the arm 14 and the forward portion of said projection 12 (relatively to the direction of feed) is filled in by an upwardly-flared web 40. 95

Looking at Fig. 2, the feed will be in the direction indicated by dotted lines, and it is apparent that as the work is fed the protruded

ends of the pegs will be caused to impinge upon the portion of the cutter that projects diagonally in a curved line across their path, thus severing such ends by an angular drawing action.

5 My object in making the cutter annular and securing it against displacement by the sleeve shown is to enable the cutting edge to be shifted around its axis, as the portion thereof 10 most frequently used becomes dull, while by lowering or raising the screw 16 the work-supporting plate 30 can be set in a plane to either conform to that of the cutting edge, and thus sever the ends of the pegs flush with 15 the work, or in a higher plane to cause the ends to be severed with a portion projecting slightly through the work, as is sometimes required, the flared web 40 preventing the cut-away portions jamming in the passage 13.

20 What I claim is as follows:

1. In a pegging-machine, a horn or work-support formed with an annular stationary part; a cutter consisting of a ring having its inner edge sharpened, and rigidly mounted 25 upon said annular part and concentrically thereof and said annular part having its perimeter screw-threaded, a retaining-sleeve having its upper edge diminished in interior diameter to bear upon said ring and having the 30 interior of its lower portion screw-threaded to take into the screw-threads of said annular part; a centripetally-extending arm formed on the interior of said annular part; a vertically-adjustable screw carried by the 35 inner end of said arm; an upwardly-flared web connecting one side of said arm to the adjacent portion of said annular part; and a work-supporting plate secured to said arm and resting upon said vertically-adjustable

screw, substantially as described and for the 40 purpose set forth.

2. In a pegging-machine, a horn or work-support formed with an annular stationary part, a cutter, mounted on said annular stationary part, a centripetally-extending arm 45 formed on the interior of said annular part and an upwardly-flared web connecting one side of said arm to the adjacent portion of said annular part, substantially as and for the purpose set forth.

3. In a pegging-machine, a horn or work-support formed with an annular stationary part, a cutter, mounted upon said annular stationary part, a centripetally-extending arm formed on the interior of said annular part, 55 a vertically-adjustable screw carried by the inner end of said arm; and a work-supporting plate resting upon said screw and secured to said arm, substantially as and for the purpose set forth.

4. In a pegging-machine, a horn or work-support formed with an annular stationary part, a cutter, mounted upon said annular stationary part, a centripetally-extending arm on the interior of said annular part and an 65 upwardly-flared web connecting one side of said arm to the adjacent portion of said annular part, a vertically-adjustable screw carried by the inner end of said arm; and a work-supporting plate resting upon said screw and 70 secured to said arm, substantially as and for the purpose set forth.

In testimony whereof I have affixed my signature in presence of two witnesses.

ELOUILD DUPLESSIS.
